UNITED STATES PATENT OFFICE.

JABEZ L. RHODEBACK, OF NEW-WAY, OHIO.

IMPROVEMENT IN FEED-RACKS.

Specification forming part of Letters Patent No. 130,867, dated August 27, 1872.

Specification describing a new and Improved Revolving Feed-Rack, invented by JABEZ L. RHODEBACK, of New-way, in the county of Licking and State of Ohio.

Figure 1 is a side view, and Fig. 2 an end view, of my improved feed-rack.

Similar letters of reference indicate corresponding parts.

This invention relates to a new rotary feed-rack, the nature of which is explained by its name. It can be turned or reversed, to be cleaned, and is so arranged that the animals can feed from the ends. The invention consists in composing the rack of rods, which cross a horizontal beam or scantling, and form four racks of which either one can at any time be used.

A in the drawing represents a horizontal beam or scantling of prismatic or other form and suitable length. Through it are fitted rods *a* at the requisite distances apart, and crossing the scantling at right angles alternately.

At the ends of the scantling are fitted through the same shorter rods *b b*, at angles of forty-five degrees to *a*. They are to prevent the animals from climbing into the ends of the rack, and serve also as handles for turning the rack. The apparatus can be supported on the lower ends of the longer rods *a* and filled from above. Whenever it is to be cleaned it is turned. It may in some cases also be hung at the ends of the beam A in journals, to be the easier turned, but should, in that case, have devices for locking it in each of its four positions.

Having thus described my invention, I claim as new and desire to secure by Letters Patent—

The revolving feed-rack herein described.
JABEZ L. RHODEBACK.
